Specification for Design.

Patented Aug. 30, 1921.

Application filed December 15, 1920. Serial No. 430,981. Term of patent 14 years.

To all whom it may concern:

Be it known that I, FREDERICK W. MOFFAT, a subject of the King of Great Britain, residing in the town of Weston, county of York, Province of Ontario, Canada, have invented a new, original, and ornamental Design for an Insulator-Support for Electrical Heating Elements, of which the following is a specification, reference being had to the accompanying drawing, forming part thereof.

In the drawings—

Figure 1 is a side view of my design for

insulator support for electrical heating elements, and

Fig. 2 an end view of the same, showing my new design.

I claim:

The ornamental design for an insulator support for electrical heating elements, as shown.

Signed at Toronto, Can., this 10th day of December, 1920.

FREDERICK W. MOFFAT.
